SET INDICATOR AID FOR MICROMETERS

Gordon E. Clauser, Elyria, Ohio

Application August 14, 1947, Serial No. 768,692

6 Claims. (Cl. 33—166)

1

My present invention relates to the general class of geometrical instruments, or micrometers, and more specifically to an improved set indicating aid for micrometers of the type employing opposed contacts with screw adjustment, and especially adapted for measuring short distances, lengths and angles, and for caliperizing diameters of cylindrical bodies.

The primary object of the invention is the provision of a guide device for setting the micrometer to aid in enhancing and increasing the operating speed of the instrument for precision measuring and caliperizing, and the invention includes a minimum number of component parts that may with facility be manufactured at low cost of production, and assembled with convenience on a conventional micrometer of this type, to insure an easily operated and precise measuring instrument.

The invention consists in certain novel features of construction and combinations and arrangements of parts as will hereinafter be described, and more particularly set forth in the appended claims.

In the accompanying drawings I have illustrated a complete example of a physical embodiment of my invention wherein the parts are combined and arranged in accord with one mode I have devised for the practical application of the principles of my invention. It will, however, be understood that changes and alterations are contemplated and may be made in these exemplifying drawings and mechanical structures, within the scope of my claims without departing from the principles of the invention.

Figure 1 is an assembly view showing a conventional micrometer equipped with the high and low setting rings of my invention; and Figure 2 is an enlarged view of a portion of the instrument disclosing the barrel of the instrument having an annular groove or channel to accommodate the setting rings.

Figures 3 and 4 are respectively an edge view and a face view of one of the setting rings or indicator rings;

Figures 5 and 6 are respectively an edge view and a face view of another indicator or setting ring; and

Figures 7 and 8 show an edge view and a face view respectively of the intermediate resilient or elastic frictional coupling ring or expander.

In order that the general arrangement and utility of parts may readily be understood I have shown in the assembly view Fig. 1 a conventional micrometer including the rotary cylindrical bar-

rel 1 mounted on a fixed cylindrical base 2, which is provided with a central vertical bore 3, and a central bearing yoke 4, which is provided with a central bearing 5 journaled in the base 2, and a screw bar 6, which is journaled in the bearing 5, and terminates in a movable or adjustable contact point 8, the knurled barrel 1 being employed for adjusting the screw bar 6 in customary manner.

As best seen in Fig. 2 in carrying out my invention the barrel 1 is fashioned with an exterior groove or channel which forms two spaced circular shoulders or walls 10 and 11 that are adapted to receive and retain a pair of rotatable split resilient rings, or high and low indicators, which are resiliently and frictionally coupled together to permit a jointly rotary movement

5 within the channel and between its walls, and also to permit relative movement of the two rings within the channel, as an aid in setting the instrument.

The forward or front indicator ring 12, which

10 has an exterior diameter slightly greater than

15 the outer diameter of the barrel, is equipped with

20 a short lateral pointer 13 flush with its exterior

25 periphery, that projects longitudinally of the

30 barrel for co-action with the tapered scale 2.

This indicator ring of elastic or resilient

35 material is split at 14 so that it may readily be

40 slipped over the barrel end into the annular

45 channel in assembling the parts, and the ring

is fashioned with a plane front face for frictional

50 contact with the wall 10 of the channel. The

rear, or coupling face 15 of the ring is serrated,

55 or provided with radial teeth for co-action with

an intermediate coupling ring or expander 16,

which is fashioned of resilient material and split

55 at 17 for mounting on the grooved barrel.

The body of the coupling ring is fluted as at

17 to provide double, or dual, serrated faces,

60 that co-act with a second, similar, indicator ring, as well as the ring 12.

The second ring 18 of resilient material is also

65 split for readily slipping into place, and it is the

70 first ring to be seated in the channel, after which

75 the coupling ring 16 and the front ring 12 are

successively seated.

The ring 18 is mounted in the channel with

80 its plane face in frictional contact with the wall

85 11, and this ring, which is equipped with a longer

90 longitudinally extending, outset or offset pointer

95 19, is provided with a serrated face 20 for co-

99 action with the resilient expander or coupling

ring 16. As indicated in Fig. 1 the pointers 13 and 19, although of varying lengths, terminate jointly for magnification with the graduations of the scales, and the offset or outset relation of pointer 19 with respect to pointer 13 permits relative movements of the pointers without interference.

The resilient intermediate expander or coupling ring in frictional engagement at its opposite sides with the two indicator rings exerts sufficient pressure or force to create the required friction for retaining the three rings in operative relation. By grasping the three rings between a thumb and finger they may be jointly revolved or rotated, and with equal facility a selected one of the indicator rings may manually be turned with relation to the other ring and the barrel, in caliper operations in connection with the adjustment of the two contact heads by means of the operating screw.

Having thus fully described my invention, what I claim as new and desire to secure by Letters Patent is:

1. In a micrometer of the opposed contacts and screw operated type, the combination with a barrel having an annular graduated scale and an annular exterior channel forming spaced side walls, of a plurality of indicator rings mounted in the channel in frictional engagement with the walls, parallel pointers rigid with the rings, respectively, and extending laterally from the same toward the scale and an elastic coupling ring between and frictionally engaging said indicator rings.

2. In a micrometer of the opposed contacts and screw-operated type, the combination with a barrel having an annular graduated scale and an annular exterior channel forming spaced side walls, of a plurality of split resilient indicator rings mounted in the channel in frictional engagement with the walls, pointers rigid with said rings, respectively, and extending laterally from the same toward the scale and a split elastic coupling ring between and frictionally engaging said indicator rings.

3. An aid for setting a micrometer including a barrel having a graduated scale and exterior laterally spaced annular walls, a plurality of indicator rings each having a pointer extending toward the scale, said rings frictionally engaging

said walls, and an intermediate elastic coupling ring frictionally engaging adjoining faces of the indicator rings.

4. In a micrometer of the opposed contacts and screw operated type, the combination with a barrel having exterior annular walls spaced laterally thereon and a graduated scale, of a plurality of indicator rings each mounted in frictional contact with a wall respectively, a pointer on each of said rings extending toward the scale, said rings having serrations on adjoining faces, and an intermediate coupling ring having opposed serrated faces in frictional engagement with the serrations of the indicator rings.

5. In a micrometer of the opposed contacts and screw-operated type, the combination with a barrel having exterior annular walls spaced laterally thereon and a graduated scale, of a plurality of split resilient indicator rings mounted in frictional contact with said walls, respectively, a pointer rigid with each ring and extending toward the scale, said rings having serrations on adjoining faces, and an intermediate split resilient coupling ring having opposed serrated faces in frictional contact with the serrations of the indicator rings.

6. In a micrometer of the opposed contacts and screw operated type, the combination with a barrel having exterior annular walls laterally spaced thereon and a graduated scale, of a plurality of indicator rings frictionally engaging said walls, respectively, and resilient means between adjoining faces of said rings whereby said rings may be rotated jointly or relative to each other on said barrel.
